DEVICE FOR SETTING AND CONTROLLING BACKFIRES

Filed June 7, 1949

UNITED STATES PATENT OFFICE

2,607,336

DEVICE FOR SETTING AND CONTROLLING
BACKFIRESAmbrose B. Everts, Seattle, Wash., dedicated to
the free use of the People in the territory of the
United States

Application June 7, 1949, Serial No. 97,692

1 Claim. (Cl. 126—271.2)

(Granted under the act of March 3, 1883, as
amended April 30, 1928; 370 O. G. 757)

1

This application is made under the act of March 3, 1883, as amended by the act of April 30, 1928, and the invention herein described, if patented in any country, may be manufactured and used by or for the Government of the United States of America for governmental purposes throughout the world without the payment to me of any royalty thereon.

I hereby dedicate the invention herein described to the free use of the People in the territory of the United States to take effect on the granting of a patent to me.

This invention relates to fire control and has among its objects provision of a device for setting and controlling back fires in grasslands or the like, which is of a simple construction carried directly on the back of a land vehicle, such as a fire engine, which may be easily raised to inoperative position for transportation to and away from grassland fires or lowered to operative position, and which may be quickly adjusted so as to set a fire on either side of the direction of travel of the vehicle by throwing a flame to that side and to extinguish the fire on the opposite side by spraying the grassland with a fire extinguishing fluid such as water on that side.

In general, according to the invention, the device has a rearwardly extending support for attachment to the back of a land vehicle. A flame thrower is pivotally mounted on this support to move horizontally, so that by simply adjusting it to either side of the support on its pivotal mounting, it is properly set to throw the flame to the desired side of the line of travel of the vehicle. A fire extinguishing fluid sprayer is also pivotally mounted on the support to move horizontally, thus providing a simple means for adjusting it to spray the grassland on the side opposite to that of the flame thrower.

Preferably, the support itself comprises tubes through which the fuel for the flame thrower and fluid for the sprayer are carried. Also, the support is preferably provided at its forward end with a vertically pivotal mounting adapted to be attached to the back of the land vehicle, whereby the support readily may be raised to inoperative or lowered to operative position, and is provided with a runner to ride over the land surface while the device is in operation and with a resilient element attached to the support and adapted to be attached to the land vehicle, quickly to return the support to operative position after the runner engages and rides over an obstruction.

For a detail description of the invention, reference is made to the accompanying drawing, in which:

2

Figure 1 is a three-dimensional view showing the device attached to the back of a fire engine, the fire engine, fuel and water tanks, and control panel being shown schematically;

5 Figure 2 is a section on the line 2—2 of Figure 1; and

Figure 3 is a section on the line 3—3 of Figure 1.

In the drawing, the fire engine 11 is of conventional design.

The device proper is provided with a main support 12 made up of four parallel rigid rearwardly extending tubes 13, 14, 15, and 16 secured together as by welding. This support is secured to the back of the fire engine by a pivotal joint 17 so that it may be raised to inoperative position. When in operative position, as shown in the drawing, the support is held against side sway by flexible chains 18 and 19, a runner 20, such as a sled, for riding over the land being secured to the support. If the runner engages obstructions, it rides over them, a resilient element 21 secured thereto and to the truck operating quickly to return the support to operative position.

25 A flame thrower 25, provided with an ignition spark plug 26 and designed to mix and burn a fuel comprising oil and gas, is of a usual design. This flame thrower is pivotally mounted on a bracket 27 as at pivot 28 and locked in position with wing nut 29. The bracket is pivotally mounted on the main support as at pivot 30. Thus, the flame thrower may be easily and quickly adjusted so as to throw the flame to either side simply by swinging it to the desired side on the pivot 30 and locking it in position with a wing nut 31.

A fire extinguishing fluid sprayer is also mounted on the main support through an upright cylindrical bar 35. This sprayer comprises a tube 36

40 provided with several spray nozzles 37, 38, 39, 40 and 41 communicating with the tube. The tube is slidably and pivotally mounted on the bar by a bearing 42 attached near one end of the tube. Thus, the sprayer may be quickly and easily adjusted upwardly and downwardly and to spray the grass on the opposite side to that of the flame set by the flame thrower simply by swinging the tube 36 to its desired position on its bearing and locking it in this position with a set screw 43.

45 50 Fuel for the flame thrower and water for the sprayer are supplied from conventional type oil, gas and water pressure tanks 50, 51, and 52, respectively, carried in the fire engine. Oil flows from its tank through a flexible tube 53, control valve 54, flexible tube 55, tube 13, and flexible tube 56 to the flame thrower. Gas flows from its tank

through a flexible tube 57, control valve 58, flexible tube 59, tube 14, and flexible tube 60 to the flame thrower. Water flows from its tank through a flexible tube 61, strainer 62, control valve 63, flexible tube 64, tube 15, and flexible tube 65 to the extinguisher tube 36.

Ignition of the fuel is provided by a battery 70, push button switch 71, and ignition coil 72 of a conventional buzzer type, the high tension, flexible spark plug wire 73 leading from the coil through tube 16 to the spark plug and being supported near the flame thrower by a rigid member 74 thus to protect the wire from overheating.

Control valves 54, 58 and 63 and switch 71 are preferably arranged on a panel board 80 which, due to the flexibility of the various tubes leading to it, may be located at any convenient place in the fire engine. As shown, the water strainer 62, battery 70 and ignition coil 72 are also on the panel board, but this is not necessary.

In use, the fire engine is driven along a line where it is desired to set the back fire with the flame thrower and sprayer set in proper positions. The operator by opening the fuel and water control valves and closing the switch 71 starts the flame thrower and sprayer thus to set the back fire in the desired direction.

I claim:

A device for setting and controlling back fires comprising a rearwardly extending support for attachment to the back of a land vehicle, a flame thrower pivotally mounted on the support so that it may be moved horizontally and set to throw the flame to either side of the line of travel of the vehicle, and a flame-extinguishing fluid sprayer pivotally mounted on the support so that it may be moved horizontally and set to throw a

spray to the side of the line of travel opposite to that of the flame thrower, said support being provided at its forward end with a pivotal mounting adapted to be attached to the back of the vehicle so that the support, flame thrower, and sprayer may be raised to inoperative position and lowered to operative position, being provided with a runner to ride over the land surface when the support, flame thrower, and sprayer are in operative position, and being provided with a resilient element attached to it and adapted to be attached to the vehicle quickly to return the support, flame thrower, and sprayer to operative position after the runner engages and rides over an obstruction.

AMBROSE B. EVERETT.
